G. VAN WORMER,
PEN CLAMP FOR RULING MACHINES,
APPLICATION FILED SEPT. 16, 1918. RENEWED MAY 19, 1919.

1,314,916.

Patented Sept. 2, 1919.

UNITED STATES PATENT OFFICE.

GEORGE VAN WORMER, OF HAMILTON, OHIO, ASSIGNOR OF ONE-HALF TO JOHN KAEFER, OF HAMILTON, OHIO.

PEN-CLAMP FOR RULING-MACHINES.

1,314,916.

Specification of Letters Patent. Patented Sept. 2, 1919.

Application filed September 16, 1918; Serial No. 254,265. Renewed May 19, 1919. Serial No. 298,320.

To all whom it may concern:

Be it known that I, GEORGE VAN WORMER, a citizen of the United States, and residing at Hamilton, in the county of Hamilton and 5 State of Ohio, have invented new and useful Improvements in Pen-Clamps for Ruling-Machines, of which the following specification is a full disclosure.

My invention relates to a pen clamp for 10 ruling machines and more particularly to the mechanism for distributing an equalized clamping pressure along the entire length of the clamp jaws.

An object of the invention is to provide a 15 pen clamp in which the jaws are closed toward each other under an equalized clamping pressure for their entire length, uniformly clamping all of the pens of a series placed between the jaws.

20 Another object of the invention is to structurally improve the clamp shown in my prior patent issued to me February 27, 1917, No. 1,217,370.

Reference is to be had to the accompanying 25 drawing included as a part of this specification, in which like characters of reference denote corresponding parts throughout the several views of which:

Figure 1 is a plan view.

30 Fig. 2 is a plan view of one of the jaw members looking at its inner face.

Fig. 3 is a view similar to Fig. 2 of the opposite jaw member.

Fig. 4 is a section on line 4—4, Fig. 1.

35 Fig. 5 is a right hand elevation.

Fig. 6 is a section on line 6—6, Fig. 1.

Fig. 7 is a detailed rear elevation of the 40 adjusting screw showing its ball and socket connection with the wedge rod.

The clamp comprises two jaws 1 and 2, each as a rectangular plate, and for their 45 particular use as a ruling pen holding clamp are usually of considerable length for holding a large number of pens to rule large sheets of paper. It is therefore essential for the jaws to have a uniform clamping pressure, and possess rigidity throughout the entire length for rigidly setting and securing all of the pens of a series. Both jaws 50 have rounded forward edges and the rear edge of jaw 1 extends beyond the jaw 2 to provide means for connecting the clamp to a cross-beam of a ruling machine.

The jaw 1, being of wood, has its inner 55 surface at its biting edge, and its entire outer

surface covered by a sheet of aluminum 3 which in practice has been found to contain properties which make it non-impregnable to ink and upon which the ink will not spread from one pen to another. These 60 features are extremely important, for heretofore considerable difficulty has been experienced in keeping clamps clean and avoiding their becoming impregnated with ink. An ink impregnated clamp will 65 destroy the tint if a change in the color of ink is made.

An anchor strip or rod 5, half rounded in section, is recessed into the inner surface of the jaw 1 longitudinally and preferably extends the entire length of the jaw, with the plane surface of the strip flush with the inner face of the jaw. The strip 5 is rigidly secured to the jaw 1 by screws, providing an anchor for a series of stirrups 6, and also 70 a reinforcement for the jaw. The stirrups 6 are spaced apart a suitable distance and are of a number depending upon the length of the clamp, each stirrup being bored at each end, one end pivotally engaging with 75 the anchor strip 5 and the other end projecting through a slot in the jaw 2 beyond the outer surface of said jaw, for engagement by a cam or wedge rod 7. The rod 7 extends longitudinally of the jaw 2 and 80 through the bore of the exposed ends of all of the stirrups of the series. The jaw 2 is counter recessed at the stirrup locations to accommodate for the ends of the stirrups which are rounded to allow the stirrup to 85 swivel free upon the anchor rod 5.

The jaw 2 has a bearing plate 8 recessed into its outer surface longitudinally along the line of the cam or wedge rod 7 engagement apertured as the jaw to receive the 90 stirrups therethrough.

The cam or wedge rod 7 operates upon the bearing plate and stirrups, and in principle is substantially the same as shown and described in my prior patent issued to me 100 as aforesaid, excepting that the stirrups in their pivotal connection with the anchor rod 5 of the jaw 1, swing or move with the jaw 2 bringing all the stirrups into alignment, and will not impart any resisting or twisting strains to the wedge or cam rod to 105 destroy a uniform clamping pressure. The rod 7 has a longitudinal plane surface 9 forming a cam or wedge edge 10 engaging the bearing plate 8, when the rod is swiveled, 110

and presenting the plane surface 9 of the rod at angles to the bearing plate.

The rod 7 by reason of its plane surface, brings its circular periphery slightly eccentric to the face of the bearing plate 8, exerting a wedging pressure against the jaw 2 in swiveling the rod either to the right or left. This action forces the two jaws together. The stirrups in a series are distributed along the rod to establish a uniform clamping pressure along the entire length of the jaws.

To one end of the rod 7, projecting beyond the ends of the jaws, an arm 11 is fixed for rocking the rod. The free end of the arm is tubular and slotted to provide a socket for the ball end 12 of the adjusting screw 13, the adjusting screw 13 having a threaded engagement through a boss 14 extending from an angle plate 15 secured to the end of the jaw 1. One limb of the angle plate reaches across the end of the jaw 2, and forms a journal for the rod 7. Turning the adjusting screw swings the arm 11, rocking rod 7. The ball end of the screw 13 normally is confined within the longitudinal socket of the arm 11 as its diameter is larger than the slot 18 through which the neck portion 16 of the screw projects. The socket of the arm 11, however, is open at the end to permit the ball end of the screw to be withdrawn from the socket for disengaging the parts, adapting the rod to be withdrawn longitudinally from its engagement with the stirrups for disassembling the parts. The parts provide a separable, universal joint producing an anti-friction, pivotal and slipping connection freely accommodating for the variations of the angle between the arm and screw in jaw clamping and unclamping motions, and non-separable within the normal degree of movement required for clamping and releasing the ruling pens between the jaws. The turning of the screw imparts motion to the parts in either direction and is aided in one direction by flat, blade springs 17 disposed between the jaws, secured to the jaws 2 and bearing against the jaw 1. Secured to the inner pen engaging edge of the jaw 2, by gluing or cementing, is a cushion strip 20 of rubber or other suitable material, providing a yielding grip surface in which the inserted pens are partially embedded to prevent lateral displacement and to compensate for slight variations in pen thickness.

Having described my invention, I claim:

1. A pen clamp for ruling machines comprising two clamp jaws, a series of stir-

ups each pivotally connected to one jaw and extending and passing through the second jaw, and a rod extending longitudinally of said second jaw and engaging with said stirrups and said second jaw for coupling said parts and when rocking imparting a clamping pressure to both of said jaws.

2. A clamp of the nature disclosed comprising two jaws, a series of spaced stirrups each pivotally connected to one jaw, and extending and passing through the second jaw, a wedge rod engaging with said stirrups and second jaw adapted when rocked to bring said jaws together, and means for rocking said rod connecting therewith and mounted at one end of one of said jaws.

3. A clamp of the nature disclosed comprising two jaws, one thereof having a stirrup anchoring rod recessed within its inner surface, a series of spaced stirrups each pivotally engaged with said anchoring rod and extending and passing through the second jaw, a rod member extending longitudinally of said second jaw engaging said stirrups and adapted when rocked to engage said second jaw for forcing said jaws together, and means for rocking said rod.

4. A clamp of the nature disclosed comprising two jaws, a series of stirrups connecting with one jaw and extending and passing through the second jaw, a rod extending longitudinally of said second jaw engaging with said stirrups, said rod adapted when rocked to force said jaws together, an arm fixed on one end of said rod having a tubular end notched longitudinally, and an adjusting screw mounted upon the end of one jaw, having a ball end socketed into said tubular end of said arm.

5. A clamp of the nature disclosed comprising two jaws, tension means between said jaws for forcing the same apart, a series of stirrups connecting with one jaw and extending and passing through the second jaw, a rod extending longitudinally of said second jaw engaging with said stirrups, said rod adapted when rocked to force said jaws together, an arm fixed on one end of said rod, having a tubular end, notched longitudinally, and an adjusting screw mounted upon the end of one jaw, having a ball end socketed into said tubular end of said arm.

In witness whereof, I hereunto subscribe my name, as attested by the two subscribing witnesses.

GEORGE VAN WORMER.
